CLAIM

The ornamental design for a TPMS tool, as shown and described.

DESCRIPTION

FIG. 1 is a right-side perspective view of a TPMS tool of the present invention.

FIG. 2 is front view of FIG. 1.

FIG. 3 is a rear view of FIG. 1.

FIG. 4 is a top view of FIG. 1.

FIG. 5 is a bottom view of FIG. 1.

FIG. 6 is a left side view of FIG. 1.

FIG. 7 is a right side view of FIG. 1.

FIG. 8 is a partial enlarged view of a portion of FIG. 4; and,

FIG. 9 is a partial enlarged view of a portion of FIG. 3. The broken lines shown are included for the purpose of illustrating portions of the TPMS Tool that form no part of

the claim.
